UNITED STATES PATENT OFFICE.

CHARLES R. MOORE, OF MAPLEWOOD, NEW JERSEY, ASSIGNOR TO WESTERN ELECTRIC COMPANY, INCORPORATED, OF NEW YORK, N. Y., A CORPORATION OF NEW YORK.

VIBRATION-RESPONSIVE DEVICE.

Application filed March 26, 1923. Serial No. 627,729.

To all whom it may concern:

Be it known that I, CHARLES R. MOORE, a citizen of the United States, residing at Maplewood, in the county of Essex, State of New Jersey, have invented certain new and useful Improvements in Vibration-Responsive Devices, of which the following is a full, clear, concise, and exact description.

This invention relates to mechanical coupling devices, and more particularly relates to coupling devices for acoustic vibrating systems such as telephone transmitters, receivers, phonograph reproducers and the like.

An object of this invention is to provide a non-rigid elastic and dissipating coupling arrangement between a driving member and a driven member whereby the moving system will transmit mechanical vibratory energy without appreciable resonance effects. A further object is to provide an improved mounting for phonograph reproducers and the like.

This elastic coupling arrangement comprises in one form of this invention, thin sheets of metal foil or paper loosely packed between the driving and driven elements to a degree sufficient to provide such a dissipation of the impressed energy as to give the desired damping. The damping effect of the coupling means is preferably secured from the thin layers of air contained between the foil sheets and for that reason the sheets need not be made of heavy material, and in general, foil light in weight such as aluminum foil will be quite satisfactory. With such an arrangement the dissipation is due principally to the pressure on the sheets causing the air between the sheets to be forced out and in for each vibration. In employing such a coupling means to a specific type of acoustic device, such as an electric phonograph reproducer, the phonograph needle by a suitable lever arm may be attached to a diaphragm or plunger which in turn is connected to the flexible wall of a carbon chamber through the intermediary of a large number of the foil sheets packed between. When the needle is traversing a sound record the mechanical vibrations of the lever arm will be conveyed to the carbon chamber by the compression and expansion of the foil sheets. Due to the presence of the foil sheets, any resonance effect in the reproducer will be substantially

reduced and the variations in the current flowing through the carbon button will, therefore, be a more faithful copy of the sound record. There will also be an appreciable reduction in the motion of the side wall of the carbon chamber as compared to the motion of the end of the needle stylus bar. Such a reduction is of considerable importance, since in general, it is unsatisfactory to fix rigidly the end of the stylus bar to the diaphragm or plunger which varies directly the pressure on the carbon granules due to the fact that the maximum permissible motion of the plunger or diaphragm is much less than the usual motion of the stylus bar.

Referring to the drawings:

Fig. 1 represents this invention embodied in a telephone transmitter.

Fig. 2 is a modification of this invention in which the foil sheets are disc shaped.

Fig. 3 is a modification in which the foil packing composes annular rings having openings of different sizes.

Fig. 4 is a modification in which the packing composes discs of varying diameters.

Fig. 5 discloses a form of this invention in which solid discs alternate with annular rings to form the packing arrangement.

Figs. 6 and 7 represent this invention as applied to piezo-electric crystals.

Figs. 8 and 9 show an alternative arrangement for employing this invention with piezo-electric crystals.

Figs. 10 and 11 illustrate this invention in a phonograph reproducer.

Fig. 12 illustrates a push-pull phonograph reproducer employing this invention.

Referring more particularly to Fig. 1, a telephone transmitter is disclosed therein comprising a carbon chamber 16 of the barrier button type, for example, as disclosed in my copending application Serial No. 505,060, filed October 3, 1921. The carbon chamber comprising a circular plate or electrode 17 separated from the front electrode 18 by an annular ring 19 of insulating material which serves as a barrier between the electrodes. A lead in wire 20 is connected to the back electrode 17 and a lead in wire 21 due to the metallic connection between the metallic case 22, and the metallic cup 23 is connected to the front electrode 18, so that, variations in the pressure exerted on the carbon granules may vary

the current flow in a suitable electric circuit connected to leads 20 and 21. The bottom of the cup shaped member 23 is covered with an insulating strip 27 which serves to insulate member 23 from the electrode 17. The barrier 19 and electrode 17 are held in place by the flange portion of the annular ring electrode 18 which is threaded with the inner side of the casing 23.

10 The front of the carbon chamber is closed by a thin disc 24 of insulating material, such as mica. Between the diaphragm 15 and the closing disc 24 of the carbon chamber are a plurality of thin annular rings 25. A plurality of similar thin annular rings 26 are included between the annular electrode 18 and the flexible wall 24 of the carbon chamber. The vibration of the diaphragm 15 due to the impressed sound waves, for example, will be transmitted through the discs 25 to the flexible wall 24 of the carbon chamber thereby causing the pressure upon the carbon to be varied in accordance with the impressed sound waves, and the variation in the pressure on the carbon will produce variable electric currents in the circuit connected to leads 20 and 21 in the well-known manner.

It will be noted that the sole connection between the diaphragm and the flexible wall 24 of the carbon chamber is through the intermediary of the thin annular rings 25 which are packed therebetween. These thin annular rings may be made, for example, of paper or thin metallic foil having a thickness as small as .001 of an inch or less. Due to the fact that these thin sheets are loosely packed there will be located thin films of air between adjacent sheets so that when vibrations are impressed upon the diaphragm 15 the air between the sheets will be forced in and out for each complete vibration of the diaphragm. When the air is expelled in this manner the coupling between the diaphragm and the flexible wall of the carbon chamber may be termed a resistance or frictional coupling. For the upper range of speech or music frequencies the resistance coupling is supplemented by what may be called an elastic coupling, due to the vibrations occurring rapidly enough that all of the air in the air films does not have sufficient time to escape but is compressed and expanded instead. Since the elastic coupling factor will increase with frequency an efficient reproduction of the tones or notes of high pitch will be insured and these tones may often be over-emphasized if in some cases it is found desirable to do so. The resistance coupling due to the expulsion of the air between adjacent sheets has been found to give sufficient damping or dissipation of the impressed energy whereby resonance effects in the moving system of the acoustic device may be smoothed out or substantially eliminated.

The thickness of the air film between adjacent sheets may vary with different uses of this invention and a thickness of .00025 to .0005 in. has been found satisfactory in most instances. The diameter of the sheets preferably should be slightly less than the diameter of the casing containing, a difference of the order of .01 generally being sufficient.

It is particularly desirable that the foil sheets or rings should be light in weight so that their combined weight is negligible compared to the mass of the remainder of the moving system. The number of sheets employed between the diaphragm and the flexible wall as well as their character and disposition will depend upon the amount of damping and kind of coupling, i.e. resistance or elastic, desired in any particular case, so that the particular arrangement disclosed in Fig. 1 may be modified to a substantial degree in other embodiments and uses of the coupling arrangement of this invention. In some cases an essentially resistance coupling may be desired for example, while in other cases an essentially elastic coupling may be preferred.

It is to be understood that the coupling means between the driving and driven members may comprise thin annular rings of uniform size or solid sheets or a combination of the two in any desired manner. For example, in Fig. 2 the driving and driven members 29 and 30 which are coupled to diaphragms or plungers 31 and 32 in a suitable housing 33 are coupled by a large number of thin but solid foil sheets 34. These diaphragms or plungers 31 and 32 are separated respectively from the end walls of the casing 33 by thin foil annular rings 35 and 36.

A second modification is shown in Fig. 3 in which the driving and driven members 37 and 38 are coupled by a large number of thin annular rings 39 having the openings in the rings of varying diameters, whereby a cone-shaped air pocket is provided between the two plungers or diaphragms 40 and 41. Such an air pocket between the driving and driven members may in some cases be of particular utility in securing the degree and kind of coupling and damping desired.

In Fig. 4 the driving and driven members 42 and 43 are coupled by solid thin discs 44 of variable diameter.

Still another possible modification of this invention is disclosed in Fig. 5 in which the driving and driven members 45 and 46 are coupled by a plurality of thin sheets 47, some of which are discs and others are annular rings. If the discs are alternated with the annular rings, additional air pockets are provided due to the openings in the annular rings being closed on either side by one of the discs. The air in the pockets will be

squeezed in and out as the vibrations of the driving member 45 are being impressed upon the driven member 46.

The coupling arrangement of this invention is also of considerable utility in the embodiment of piezo electric crystals for translating mechanical vibrations into variations of electrical energy. As disclosed and claimed in the United States Patent No. 1,495,429 to Alexander MacLean Nicolson dated May 27, 1924, subject piezophony, pressure variations applied to a piezo-electric crystal may be translated into variations of electrical energy. One way in which the pressure variations may be impressed upon the crystal is by means of the coupling arrangement of this invention as shown in Figs. 6 and 7. The crystal 48 is rigidly attached at one end to a suitable support 49 and the other end of the crystal is included between a large number of foil sheets 50 enclosed in a suitable housing 51. This housing 51 is rigidly attached to a needle holder 52 which holds a suitable needle 53 capable of undergoing vibrations due to its traversing a sound record 54 such as a phonograph record. The vibration of the needle 53 will therefore cause the housing 51 to vibrate in a plane at right angles to the plane of the drawing and this vibration through the intermediary of the thin sheets 50 will exert corresponding variations in pressure upon the crystal 48. These variations in pressure as disclosed in the above mentioned Nicolson patent will give rise to variable electro motive forces which may be employed in any manner desired.

The coupling between the needle holder and the crystal may also be made in the manner disclosed in Figs. 8 and 9 in which one end of the crystal 55 is held rigidly between a clamp 56. An extension of this clamp comprises a hollow cylinder 57 along the axis of which is located the needle holder 58 held in position solely by a spiral wrapping 59 of a long sheet of thin metal foil or paper. The motion of the needle holder 58, due to the needle traversing a sound record will be transmitted through the motion of the needle holder 58, to cause variations in pressure exerted on the crystal 55 due to the intermediary of the damping action of the foil wrapping 59. This coupling arrangement has been found to produce a faithful reproduction of the sound record in a much more satisfactory manner than if the needle holder were rigidly connected to the crystal due to the fact that the needle holder 58 of course must undergo an appreciable vibratory motion while the crystal 55 should be subjected only to variations in pressure without appreciable motion being required.

Another modification of this invention is shown in Figs. 10 and 11 in which a carbon-carbon button phonograph reproducer is disclosed

in which the coupling arrangement between the lever arm of the needle holder and the flexible wall of the carbon chamber is obtained by means of the foil packing arrangement of this invention. A barrier button carbon chamber is disclosed having for its back electrode an annular ring 60 separated from the front electrode 61 by an annular ring 62 of insulating material which constitutes the barrier as disclosed in my above mentioned application. The carbon chamber is enclosed by a flexible wall 63 of insulating material which is flexibly separated from the electrode 61 by a few annular sheets 64 of thin foil. The lever arm 66 of the reproducer is connected at one end in a suitable manner to a needle holder 64 and at the other end is rigidly connected to the center of a diaphragm or plunger 67. Included between the plunger 67 and the flexible wall 63 of the carbon chamber is a packing of a plurality of thin annular rings 68 which forms a dissipating coupling between the plunger and the closure of the carbon chamber to give the desired amount of damping to the vibrations of the moving system of the reproducer. These rings 68 as described above may consist of aluminum foil of a thickness of one-thousandth of an inch or less whereby the dissipation of the mechanical energy and the resulting damping is due principally to the air films between the various sheets of the packing and not due to the inertia of the packing. That is, the damping should be due principally to the energy required to force out the air enclosed between the foil sheets. If desired, thin annular sheets 69 may be employed to provide a flexible separation between the plunger 67 and the closing member 70 of the reproducer.

The above coupling arrangement between the flexible wall of the carbon chamber and the lever arm of the reproducer has been found to suppress to a very substantial degree any unnatural response of the reproducer for any frequency or band of frequencies which tends to be present in undesired amounts due to resonance effects of the moving system and the closeness of the coupling can be made to vary with frequency and amplitude.

A modification of the arrangement of Fig. 11 is disclosed in Fig. 12 in which the invention is shown embodied in a carbon phonograph reproducer of the so-called push-pull type. The housing 70 includes a suitable cylindrical support 71, in each end of which is threaded a barrier button carbon chamber. Each carbon chamber comprises a back electrode 72 substantially hemispherical in form separated from the front electrode 73 by the barrier 74 of insulating material. The flexible member 75 of the carbon button is separated from the front electrode 73 by a few thin annular rings 76.

to form a resilient packing. The lever arm 77 is connected at one end in a suitable manner to a reproducing needle 78, while the other end of the lever arm is positioned 5 between two dish or hat-shaped members 79 and 80 which are employed for communicating the vibrations of the sound record needle to each of the carbon chambers. The dish-shaped member 80 is not rigidly connected 10 to the flexible wall 75 of the carbon chamber, but is connected thereto solely through the intermediary of the packing comprising a plurality of discs 81 of thin metal foil such as aluminum. If desired the other side of 15 the flat portion member 80 may be supported and separated from the closing ring 82 of the carbon button by a frictional packing comprising a few sheets 83 of metal foil. The use however of metal foil between a 20 movable member and the rigid housing or support therefor is not a part of this invention but is disclosed and claimed in my co-pending application, Serial No. 505,059, filed October 3, 1921, on vibration responsive 25 apparatus.

In addition to damping the vibrations of the moving system of the reproducer the coupling arrangement 81 between the lever arm and the flexible wall of the carbon 30 chamber, also has the advantage that the motion of the end 84 of the lever arm does not cause the same amount of motion in moving the flexible wall 75 of the carbon chamber, but the flexible wall 75 will undergo a maximum motion only a fractional 35 part of the maximum motion of the end 84 of the lever arm, the fractional amount being determined for any particular case by the number and arrangement of the packing of foil sheets. This reduction in the 40 motion of the lever arm is of considerable advantage since the optimum motion for the end 84 of the lever arm is greater than the permissible motion of the closing wall of the 45 carbon chamber.

It will be apparent from the various disclosures made above that this invention may possess widely different embodiments and may be employed in a variety of ways for 50 coupling a driving and a driven member of an acoustic or other vibration responsive device without departing in any way from the spirit of this invention as defined in the appended claims.

55 The invention claimed is:

1. A vibration responsive device comprising

ing a driving member, a driven member and an air-damped coupling means between said members comprising a plurality of juxtaposed sheets of thin material with thin air 60 films therebetween.

2. An acoustic device comprising a movable member adapted to be vibrated by speech frequency vibrations, a flexible member, and coupling means between said members for causing said flexible member to be vibrated by said first member, said means comprising between said members a plurality of loosely packed layers of thin flexible material arranged to transmit vibrations 70 to said flexible member through the compression and separation of said layers.

3. A vibration responsive device comprising a driving member, a driven member, and a coupling device between said members 75 comprising a plurality of juxtaposed layers of thin flexible material of a total mass small compared to the mass of the remainder of the moving system.

4. A vibration responsive device comprising a driving member, a driven member, and an air-damped coupling device between said members comprising a plurality of juxtaposed layers of thin metal foil loosely packed between said members and arranged 80 to transmit vibrations from said driving member to said driven member through the compression and separation of said layers.

5. A vibration responsive device comprising a driving member adapted to be vibrated by speech frequency vibrations, a driven member and a plurality of thin metal foil sheets held between said members, the distance between said members being greater than the total thickness of said sheets to provide air spaces between adjacent sheets.

6. A vibration responsive device comprising a translating element, a movable member subjected to mechanical vibrations of speech frequency and spaced from said element, and an air-damped coupling means between said element and said member comprising a plurality of metal foil sheets loosely packed between said element and said member, said sheets having a combined weight negligible compared to the weight of the remainder of the moving system.

In witness whereof, I hereunto subscribe my name this 20th day of March A. D., 1923.

CHARLES R. MOORE.
